UNITED STATES PATENT OFFICE.

JOHN MATZELLE, OF CLEVELAND, OHIO.

REVOLVING WINDOW SASH.

Application filed May 4, 1921. Serial No. 466,831.

To all whom it may concern:

Be it known that I, JOHN MATZELLE, a citizen of the United States, and resident of Cleveland, in the county of Cuyahoga and State of Ohio, have invented certain new and useful Improvements in Revolving Window Sashes, of which I hereby declare the following to be a full, clear, and exact description, such as will enable others skilled in the art to which it appertains to make and use the same.

The objects of the invention are to provide a simple and efficient pivotal support for a swinging window sash, especially for a swing sash mounted between casing strips.

The pivotal support is also designed to provide means for preventing the passage of light and moisture between the sash and the casing strip when the sash is closed, without interfering in any way with the movements of the sash either when swung upon its pivots or when raised and lowered in its frame.

The invention comprises, a pivotal support formed in two portions, one portion being provided with a longitudinal V shaped ridge, and the other portion provided with a corresponding V shaped groove, the aforesaid ridge and groove registering with and being continuations of a similar ridge and groove in the meeting edges of the sash and the casing strip.

The portions include a metal plate mounted upon the sash and provided with an opening at the bottom of said V shaped groove, and with a number of shallow recesses spaced apart in a circle about the central opening, and an opposed plate mounted in the casing strip, and provided with a central projection adapted to pivot in said opening in the other plate, and also provided with spaced projections or lugs projecting from the summit of said V shaped ridge, and adapted to engage in turn with said recesses.

It includes means for securing the said plates and casing strip resiliently together, and for securing the plate for said sash to said sash.

It includes fastening devices for said sash for preventing outsiders from revolving the sash and also adapted to draw the sash and casing strip tightly together.

The invention is hereinafter described, shown in the accompanying drawings and specifically pointed out in the claims.

In the accompanying drawings, Fig. 1, is a front elevation of a window sash, a portion being broken away to show the device; Fig. 2, is a vertical section showing the two plates and resilient attaching means therefor; Fig. 3, is a perspective of the plate attached to the sash; Fig. 4, is a perspective of the plate attached to the casing strip; Fig. 5, is a view of the back of the plate attached to the sash; Fig. 6, is a perspective of the fastening means employed which serves also to draw the sash and casing strip together.

In these views A, represents the sash, and B, the casing strips, which may hang upon the casing by means of the pins O, O.

The opposed edges of the sash and casing strips are provided with weather excluding means comprising, the longitudinal central V shaped ridge C, upon each casing strip, and the central V shaped groove D, in the engaging edge of the sash. This construction permits the sash to revolve easily in the said strips, but makes a weather tight joint therewith.

The pivotal parts are constructed as follows:

A plate E, is attached by means of screws F, F, to each side of the sash and this plate is provided with a V shaped longitudinal groove G.

In the center of this groove is shown an opening H, and about the opening are circularly spaced a number of recesses I, I, I, which are positioned, two in the bottom of the groove, and the others upon the sloping sides and face of the plate.

The opposed plate J, is set in a recess in the edge of the casing strip and is provided with a V shaped longitudinal ridge K, upon the apex of which is positioned the pivot wrist L, which is inserted in the opening H, in the other plate, and upon the apex of the ridge are positioned the projecting spaced lugs or bosses M, M, which are adapted to enter the recesses I, I, I, in the other plate in turn as the sash revolves upon the casing.

A bolt or rivet O, passes through both plates and a flat spring P, concealed in a recess Q, in the sash plate engages the head

R, of the rivet, and holds the parts together.

The bolts or rivets O are extended and project longitudinally at B' beyond the casing strips and are inserted in openings O' in the window casing. Upon these extensions of the rivets the sash strips are supported, in such a manner that they will yield when the sash is revolved and will be returned by means of the springs P, P. Collars, O² on these pins force back the casing strips when the window sashes are revolved.

In Fig. 6, the fastening devices for the sash are shown which produce tight joints between the sash and strips and prevent the sash from being turned outwardly at the bottom.

Here S, is an eye normally secured to the casing strip and T, is a horizontal spring plate or projecting tongue secured to the sash, which engages the eye when the sash is closed. It is understood that the lower rail of the lower sash swings outwardly away from the operator when the sash is opened and towards the operator when the sash is closed. V, is a latch pivoted upon the casing which can be engaged with the opening W, in the projection T, when the sash is closed and prevent the sash from being revolved.

Having described the invention what I claim as new and desire to secure by Letters Patent is:

1. In a window structure comprising a casing and a sash therein, the combination with a stile member of said sash, of a strip member interposed for lateral movement between said stile and said casing, means for pivotally connecting said members, and means preventing said strip from turning with said sash, said members having respectively an inter-engageable ridge and groove, and the first mentioned means comprising a pair of plates, one having a ridge and the other a groove respectively alined with the first mentioned ridge and groove, and one plate having a tubular boss and oppositely disposed projections spaced therefrom and the other a central boss receiving opening and spaced depression disposed therearound to releasably receive said projections, a pin passing through said boss, said central opening and said strip, and provided with a head, and a collar disposed at opposite sides of said strip, and a flat spring interposed between said head and the adjacent plate.

2. In a device for the purpose described, in combination, a casing, a sash therein, oppositely disposed, non-rotatable laterally movable side strips in which said sash is pivoted for swinging movement, the vertical meeting edges of said sash and strip members being provided with inter-engaging longitudinal ridges and grooves, opposed plates upon the adjacent edges of said members, said plates being provided respectively

with corresponding grooves and ridges, the plates having ridges being also provided with central tubular bosses, and with opposite spaced projections spaced therefrom and the plates having grooves having also central openings to receive said bosses and spaced circularly arranged depressions adapted to receive said spaced projections, pivot pins passing through said central openings and bosses in said plates and through said strips, each of said pins having a head at one end and a collar engaging the adjacent strips at the other end, and a flat spring engaging said head to resiliently hold said plates together, each pin having a longitudinal extension at one end adapted to enter the casing to prevent raising said sash.

3. In a device for the purpose set forth, the combination with a casing, of a sash therein, laterally movable side strips between which said sash is revolvable, the inner vertical edges of said strips being provided with longitudinal ribs, and the outer vertical edges of said sash being provided with longitudinal grooves, opposed plates secured to the meeting edges of said sash and strips, the plates on said strips being each provided with vertical ridge and with a central tubular boss, and with opposite projections mounted upon said ridge, and each plate on said sash being provided with a longitudinal groove, and a central opening in the bottom of said groove adapted to receive said tubular boss in the adjacent plate, and with a circular row of depressions spaced about said central opening, and adapted to receive said circular row of projections, pivot pins each passing through one of said central openings and the respective boss and side strip and having a head at one end and a collar engaging said strip, the plates in said sash being provided with recesses in their backs and means in said recesses cooperating with said pins for resiliently drawing said sash and strips together.

4. In a device for the purpose set forth, the combination with a casing, of a sash therein, side strips between which said sash is revolvable, the inner vertical edges of said strips being provided with longitudinal ribs, and the outer vertical edges of said sash being provided with longitudinal grooves, opposed plates secured to the meeting edges of said sash and strips, the plates on said strips being each provided with vertical ridge and with a central tubular boss, and with opposite projections mounted upon said ridge, and each plate on said sash being provided with a longitudinal groove, and a central opening in the bottom of said groove adapted to receive said tubular boss in the adjacent plate, and with a circular row of depressions spaced about said central opening

and adapted to receive said circular row of projections, pivot pins each passing through one of said central openings and the respective boss and side strips and having a head 5 at one end and a collar engaging said strip, the plates in said sash being provided with recesses in their backs, and a spring in each recess engaging said pivot pin to resiliently secure said sash and strips in interlocking 10 positions with each other.

5. In a device for the purpose set forth, the combination with a casing, of a sash therein, side strips between which said sash is revolvable, the inner vertical edges of 15 said strips being provided with longitudinal ribs, and the outer vertical edges of said sash being provided with longitudinal grooves, opposed plates secured to the meeting edges of said sash and strips, the plates 20 on said strips being each provided with ver-

tical ridge and with a central tubular boss, and with opposite projections mounted upon said ridge thereon, and each plate on said sash being provided with a longitudinal groove, and a central opening in the bottom 25 of said groove adapted to receive said tubular boss in the adjacent plate, and with a circular row of depressions spaced about said central opening and adapted to receive said circular row of projections, a pivot pin 30 passing through the central openings in said plates, said pin having a head at one end, and a collar at the other end, the plates in said sash being provided with recesses in their backs, means in said recess for resiliently separating said plates, said pins preventing the raising of said sash. 35

In testimony whereof, hereunto set my hand this 18th day of April, 1921.

JOHN MATZELLE.
